UNITED STATES PATENT OFFICE

142,700

DESIGN FOR A COMBINATION DESK UNIT

Gio Calabrese, Brooklyn, N. Y.

Application July 2, 1945, Serial No. 120,454

Term of patent 14 years

(Cl. D74—1)

To all whom it may concern:

Be it known that I, Gio Calabrese, a citizen of Italy, residing at Brooklyn, in the county of Kings and State of New York, have invented a new, original, and ornamental Design for a Combination Desk Unit, of which the following is a specification, reference being had to the accompanying drawing, forming a part thereof:

I claim:

The ornamental design for a combination desk unit, as shown.

GIO CALABRESE.
